UNITED STATES PATENT OFFICE.

ROBERT COWEN, OF CAMBRIDGE, MASSACHUSETTS.

DESIGN FOR AN ELASTIC TIRE.

SPECIFICATION forming part of Design No. 29,988, dated January 10, 1899.

Application filed December 12, 1898. Serial No. 699,078. Term of patent 14 years.

To all whom it may concern:

Be it known that I, ROBERT COWEN, a citizen of the United States, residing at Cambridge, in the county of Middlesex and Commonwealth of Massachusetts, have invented and produced a new and original Design for an Elastic Tire, of which the following is a specification.

In the drawings accompanying and forming a part of this application, Figure 1 is a perspective view of an elastic tire, illustrating my design; and Fig. 2 is an enlarged perspective view of a section of the tire.

The leading feature of my design for an elastic tire as a unitary article (shown in the drawings) consists in a tire having upon its inner circumference two fine projections or bead-like ribs extending in the direction of the tire, parallel to each other and equidistant from the median line of the inner circumference, and separated by a smooth transversely convex surface, the outer circumference of the tire being transversely convex from one to the other projection.

The inner circumference or rim-surface of 25 the tire is shown as provided at each side of and equidistant from its center or median line with two fine parallel projections or bead-like ribs *a a*, extending continuously in the direction of the length of the tire, the ribs being 30 separated by a smooth transversely convex surface *b*, the outer circumference of the tire being transversely convex from one to the other projection.

Having fully described my invention, what 35 I claim is—

The design for an elastic tire, substantially as herein shown and described.

In testimony whereof I have signed my name to this specification in the presence of 40 two subscribing witnesses.

ROBERT COWEN.
